UNITED STATES PATENT OFFICE.

WILLIAM F. GRUMME, OF NEW YORK, N. Y., ASSIGNOR OF ONE-FOURTH TO LEOPOLD SEGAL, OF NEW YORK, N. Y.

APPARATUS FOR RAISING SHIPS.

1,344,505.

Specification of Letters Patent. Patented June 22, 1920.

Application filed February 12, 1920. Serial No. 358,265.

To all whom it may concern:

Be it known that I, WILLIAM F. GRUMME, a citizen of the United States, and a resident of the city of New York, borough of 5 Manhattan, in the county of New York and State of New York, have invented a new and Improved Apparatus for Raising Ships, of which the following is a full, clear, and exact description.

10 This invention relates to improvements in apparatus for raising ships, an object of the invention being to provide improved means for freezing the water around and in a sunken ship so that the ship with the 15 ice around the same can be brought to the surface and salvaged.

A further object is to provide an improved construction of hollow pontoon which is adapted to be lowered in the water 20 to inclose a sunken ship and which is provided with refrigerating means so that the water in the pontoon can be frozen into a solid block of ice.

25 A further object is to provide an apparatus of the character stated which is adapted to be controlled by a ship on the surface of the water so as to efficiently salvage sunken ships.

With these and other objects in view the 30 invention consists in certain novel features of construction, and combinations and arrangements of parts as will be more fully hereinafter described and pointed out in the claims.

35 In the accompanying drawings—

Figure 1 is a broken view partly in section and partly in elevation illustrating my invention; and

40 Fig. 2 is a view in transverse section through the pontoon.

1 represents my improved pontoon which is hollow and open at the bottom and provided in its wall with suitable packing 2 which renders the wall non-heat conducting 45 to prevent the interchange of temperatures of the water outside of the pontoon with that inside of the pontoon. An air casing 3 constitutes the top of the pontoon and is formed with tubular passages 4 extending 50 vertically through the air casing and the bottom 5 of the air casing which constitutes the inner upper wall of the pontoon, inclines upwardly from its side edges to its longitudinal center so that this inclination

directs the small particles of ice, as they 55 form, to the center and allows them to escape through the passages 4 to prevent an overaccumulation of ice within the pontoon which might tend to injure the same. A pipe coil 6 is supported around the inner 60 wall of the pontoon and is adapted to contain a circulating refrigerating medium. Balancing compartments 7 are provided on top of the pontoon adjacent its respective 65 ends to control the level of the pontoon while lowering it in the water as will more fully hereinafter appear.

In connection with my improved pontoon I employ a ship 8 located on the surface of the water and provide this ship 8 with all 70 necessary apparatus to perform the functions as they will hereinafter appear. A pair of circulating pipes 9 connect the ship 8 with the refrigerating coil 6 so that a refrigerant may be maintained in circulation 75 through the coil to freeze the water inside of the pontoon around the sunken ship illustrated by the reference numeral 10. A pair of pipes 11 connect the ship 8 with the air casing 3 and pairs of pipes 12 connect the 80 balancing compartments 7 with the ship 8.

The operation is as follows: The pontoon 1 is floated on the water to a point above the sunken ship and then is allowed to sink in the water. To facilitate this 85 sinking of the pontoon, water is circulated through the pipes 11 to force out the air in the casing 3. As the pontoon sinks to prevent possibility of its tipping or inclining, a flow of water and air into the balancing compartments 7 can be controlled 90 through the pipes 12 so as to maintain the pontoon at a horizontal while it is sinking.

After the pontoon is in position inclosing the sunken ship 10, the refrigerating medium 95 is circulated through the pipes 9 and coil 6 to freeze the water around the sunken ship and also inside of the sunken ship into a solid block of ice. The excess of ice as it is formed and floats to the surface will be 100 allowed to pass through the passages 4 and be directed to such passages by the inclination or shape of the bottom of the air casing 3.

After the freezing operation is finished, 105 the water can be pumped out of the casing 3 and air admitted or forced thereinto to give the necessary buoyancy to lift the block

of ice with the ship therein to the surface of the water. The ice itself being more buoyant than the water has a tendency to lift the ship and when the pontoon with the 5 block of ice therein and the sunken ship frozen in the ice reaches the surface of the water, they can be towed to a place of salvage.

While I have illustrated what I believe to 10 be a preferred form of my invention, I would have it understood that I do not limit myself to the precise details of construction but desire to cover broadly a pontoon or similar device provided with means for 15 freezing a sunken ship within a block of ice so that it can be raised to the surface of the water.

I claim:

1. An apparatus of the character described, comprising a pontoon having an 20 open bottom, and refrigerating means in the pontoon.

2. An apparatus of the character stated, comprising a pontoon having an open 25 bottom, and a pipe coil around the inner wall of the pontoon, said pipe coil adapted to contain a refrigerating medium.

3. An apparatus of the character described, comprising a pontoon having an 30 open bottom, an air casing formed at the top of the pontoon, and refrigerating means in the pontoon.

4. An apparatus of the character described, comprising a pontoon having an 35 open bottom, a lining of non-heat conducting material in the wall of the pontoon, a

refrigerating means in the pontoon, and an air casing on the pontoon.

5. An apparatus of the character described, comprising a pontoon having an 40 open bottom, refrigerating means in the pontoon, an air casing on top of the pontoon, and said air casing having passages therethrough communicating with the interior of the pontoon.

6. An apparatus of the character described, comprising a pontoon having an open bottom, refrigerating means in the pontoon, and an air casing on top of the pontoon, said air casing having its lower 50 face inclining toward its longitudinal center and having passages at its longitudinal center communicating with the interior of the pontoon.

7. An apparatus of the character described, comprising a pontoon having an open bottom, refrigerating means in the 55 pontoon, an air casing on top of the pontoon, and balancing compartments secured to the top of the pontoon and having means for 60 controlling the flow of air and water thereinto.

8. In an apparatus for raising sunken ships, the combination with a pontoon adapted to inclose a sunken ship, a ship adapted to be located on the surface of the water, and pipes connecting the ship with the pontoon, certain of said pipes controlling the flow of refrigerating medium to the pontoon and others of said pipes controlling the flow of 65 water and air to the pontoon.

WILLIAM F. GRUMME.
